UNITED STATES PATENT OFFICE.

KARL RÜCKER AND DANIËL PICKÉE, OF MARIENFELDE, NEAR BERLIN, GERMANY.

ARRANGEMENT FOR FLAMING.

1,240,606.

Specification of Letters Patent. Patented Sept. 18, 1917.

Application filed December 8, 1913. Serial No. 805,418.

To all whom it may concern:

Be it known that we, Dr. KARL RÜCKER and DANIËL PICKÉE, subjects of the German Emperor and the Queen of the Netherlands, 5 respectively, both residents of Grossbeerenstrasse 49, in the city of Marienfelde, near Berlin, Germany, have invented new and useful Arrangements for Flaming, of which the following is a specification.

10 The present invention relates to an improved arrangement for flaming, and consists in the method, including the steps and processes, and the apparatus, comprising the arrangements and combinations, all as hereinafter described and claimed.

15 The art of flaming as heretofore accomplished, generally employed a blow lamp or torch to which was supplied a gaseous fuel, preferably coal or water gas. The combustion 20 of such gases is attended with a formation of water, as will be understood, and such water deposits upon the surface to be treated so as to interfere, and at times positively prevent the progress of the flaming operation. 25 The presence of water further tends to reduce the temperature at which the operation is performed, and prohibits that high degree of heat necessary to secure the best results.

30 Prior methods employing gaseous fuels have been a source of danger from the liability of the fuels to explode, and it is to reduce such liability and to overcome the above disadvantages that the present arrangement has 35 been devised.

35 The present method consists primarily in spraying an ignited liquid hydrocarbon under pressure against the surface to be treated, and such surface may or may not previously 40 have been coated with a resinous substance, such as pitch or varnish. It will be understood that hydrocarbons, such as benzol, petrol, kerosene, and the like, undergo combustion with the formation of little, 45 if any water, and the application of the same in the liquid form operates to penetrate the resinous or other coating and to affect the surface to be treated, whereby the coating will flow freely and incorporate itself into 50 the surface so as to provide a smooth finish.

55 In the accompanying drawing is illustrated an apparatus for carrying out the above method, wherein the figure is an elevational view of a vessel, partly in section, and showing the apparatus as applied to treat the interior thereof.

Referring more particularly to the drawing, *a* designates a vessel, such as a brewery tank, provided with a manhole, as shown, and a vent at the top thereof. 60

The burner *b* is constructed to receive the liquid hydrocarbon and to direct the same against the interior of the vessel *a*, and the same is under the control of a valve *c*. The liquid hydrocarbon is supplied to the burner 65 *b* through a tube *d*, preferably of brass or copper, of one to two millimeters in diameter, and coiled as shown, to increase the flexibility of the same. The tube *d* is coupled to a valved connection *f* on a tank *e*, in 70 which the liquid hydrocarbon is contained, and the tank *e* is provided with a connection *g* for a pump, whereby the same may be placed under suitable pressure. A gage *h* is preferably mounted on the tank *e* for indicating the degree of pressure therein. It 75 will be understood that the supply of hydrocarbon may be cut off either at the burner *b* by means of the valve *c*, or at the tank *e* by the valve *f*, and the same may contain an 80 amount of fuel sufficient for an entire operation without the necessity of interrupting the operation to replenish the tank; and a single supply of air pressure will be for all purposes sufficient for each charging of said 85 tank.

It is to be understood that the arrangement herein shown and described is not restricted to the flaming of interior walls of vessels, but may equally well be applied to 90 exterior walls, ships' bottoms, and other surfaces to be treated; and the method may be employed either in connection with a coating of resinous material previously applied, or not, as desired. 95

We have illustrated and described preferred and satisfactory process and constructions, but obviously changes could be made in the herein described method and apparatus which could be used without departing 100 from the spirit of our invention.

We claim:

1. A device for flaming the inner walls of tanks and the like, especially brewery vessels, in combination, a burner for liquid fuel, 105 a reservoir for containing the liquid fuel located outside the vessel to be flamed, a metallic spirally-wound tube extending through an opening in the vessel and connecting the burner and reservoir, and a valve associated 110 with said burner and for controlling the passage of the liquid fuel to the same from the

reservoir and through said spiral tube, substantially as described.

2. An apparatus of the character described including a burner adapted to be received through an opening in a tank to be flamed and to be readily moved about therein by the operator, a reservoir situated without said tank and having means for placing the same under pressure, a thin flexible tube 10 of small diameter having its ends connected to said reservoir and burner and passing freely through the opening in said tank, a liquid hydrocarbon placed under pressure in said reservoir and passing through said tube 15 to said burner, and a valve in said burner

for controlling the issuance of said hydrocarbon in liquid form, said issuing liquid hydrocarbon being ignited and directed by the operator against the walls of the tank, substantially as described.

20

In testimony, that we claim the foregoing as our invention, we have signed our names in presence of two witnesses, this 22nd day of November, 1913.

DR. KARL RÜCKER.
DANIËL PICKÉE.
